(57) **CLAIM**

I claim the ornamental design for the laptop computer support, as shown and described.

DESCRIPTION

FIG. 1 is a top view of the laptop computer support;

FIG. 2 is a front view thereof;

FIG. 3 is a right side view of the laptop computer support, also showing a laptop computer located on the support;

FIG. 4 is a left side view thereof;

FIG. 5 is a bottom view thereof;

FIG. 6 is a back view thereof;

FIG. 7 is an isometric view of the laptop computer support, showing the front, top, and right side, and also showing a laptop computer located on the support; and,

FIG. 8 is another isometric view of the laptop computer support showing the bottom, back, and left side.

The broken line showing of portions of the laptop computer support forms no part of the claimed design.

The broken line showing of a laptop computer in FIG. 3 and FIG. 8 is included for the purposes of illustrating the laptop computer support in use and forms no part of the claimed design.
